VOLTAGE COMPENSATION

Wilfred H. Howe, Winchester, Mass., assignor to
 The Cincinnati Milling Machine Co., Cincinnati,
 Ohio, a corporation of Ohio

Application November 29, 1933, Serial No. 700,234

14 Claims. (Cl. 175—183)

This invention relates to a method and circuits for compensating for variations in a source of power, more particularly when that source is used through electrical means to energize mechanism, the response of which it is desired to make correspond to variations in a variable electrical characteristic and whereby such source variations shall be substantially or wholly without effect on the mechanism. Such a source may, for example, be a commercial source of electrical power, which, as is well known, is subject to voltage variations and fluctuations, often sudden, and which if not compensated for would disturb the response of the mechanism energized therefrom which it is desired shall be responsive only to variations in the variable controlling characteristic. The source may, however, be a different source subject to power variations which give rise to corresponding variations in voltage in associated circuits. The system of the invention acts to compensate for such voltage variations from whatever cause they may arise.

In general the compensative system of this invention comprises three portions: (a) a circuit which, for convenience, may be called a measuring circuit, including a variable impedance or other electrical characteristic to be measured, or the variations of which are employed for control or other purposes, and means responsive in a manner corresponding to variations in the variable characteristics; (b) a power conversion or control unit interposed between the power supply and the measuring circuit and having an electrical characteristic variable with variations of the power supply; and (c) a compensating connection whereby the changes in the electrical characteristic in the power conversion or control unit are fed to the responsive means in such a manner that variations in the responsive means arising from variations in the power supply are compensated for so that such power supply variations do not affect the response in the meter circuit, at least when the desired response indication is being given. This power conversion or control unit often, though not necessarily, consists of apparatus whose principal function is to receive power as conveniently available (say, 105 to 120 volts 60 cycles from the lighting circuit) and to convert this power to the form necessary for the operation of the measuring circuit (say 300 to 330 volts 1500 kilocycles for the operation of a capacity measuring circuit).

For a more complete understanding of this invention, reference may be had to the accompanying drawings in which

Figure 1 is a diagram of a resistance measuring circuit to which voltage compensation in accordance with this invention may be applied.

Figure 2 is a current voltage curve for the ballast tube used in the circuit of Figure 1.

Figure 3 is a diagram showing the effects of line voltage variation in a circuit such as shown in Figure 1.

Figure 4 is a diagram of the circuit of Figure 1 to which has been added line voltage variation compensation in accordance with this invention.

Figures 5 and 6 are diagrams showing the performance of the circuit of Figure 4 with various values of certain electrical characteristics.

Figure 7 is a diagram like Figure 4 except that the parts are differently placed.

Figures 8, 9, and 10 are diagrams of other types of measuring circuits including the voltage variation compensation of this invention.

Figure 11 is a diagram somewhat similar to Figure 8, but showing a control mechanism rather than an indicator.

Figure 12 is a view somewhat similar to Figure 9, but showing a potentiometer type of indicating circuit.

Figure 1 illustrates a measuring circuit for the measurement of a resistance R_m . The current flow through this resistance is measured by the meter M, which thereby varies with the resistance provided a constant voltage is applied. In order to obtain a constant voltage, a voltage regulator shown as a ballast tube 10 is interposed between the supply lines 11 and the measuring circuit. The regulating effect of such a ballast tube depends upon the variation of resistance of an iron wire in an atmosphere of hydrogen with variations of temperature of the iron wire due to change of current flow.

The current voltage curve for a ballast tube is shown in Figure 2. This curve shows that within the working range from 35 to 65 volts across the tube a relatively small change in voltage is accompanied by a large change in current. The performance within the working range approximates the following equation:

$$\text{Voltage} = 150 \times \text{current} - 205$$

In the circuit of Figure 1 there is a parallel resistance R_e connected in series with the tube and in parallel with the load, the value of this resistance being such that the current within the tube lies within this working range.

Figure 3 shows the performance of the circuit of Figure 1 with such a voltage regulator with a total resistance of R_e in parallel with R_m of 40 ohms.

ohms. The upper full line curve 15 shows the output voltage across the load and the curve 16 the voltage across the ballast tube both being plotted against line voltage. The dash line 17 indicates 5 the voltage variation which would exist if the resistance of the ballast tube were constant. A comparison of this curve with the curve 15 indicates the effects of the voltage regulator to reduce voltage variation on the meter resulting 10 from variations of line voltage. It will be noted, however, that the curve 15 indicates a considerable uncorrected error which would give rise to considerable possible error in the meter reading due to changes of line voltage.

15 Figure 4 illustrates a circuit of the type shown in Figure 1, but provided with a feed-back circuit in accordance with this invention. This feed-back or compensating circuit connects a fixed resistance R_s direct from the supply line to 20 the measuring resistance R_m in parallel with the ballast tube and meter M. This resistance R_s is large in comparison with that of the ballast tube, so that the current through it is small in comparison with that through the ballast tube. However, since the resistance R_s is constant, while 25 that of the ballast tube increases rapidly with increase of supply voltage, the proportion of current through R_s increases more than in proportion to the increase of line voltage. By a proper choice of the resistance of R_s , this more than proportional increase of current flow through R_s occurring with an increase of supply voltage can be made exactly equal in amount 30 to the increase of current through R_m resulting from this same increase of supply voltage incompletely regulated by the ballast tube. Under these circumstances, there will be no change in the current flow through meter M with change of line voltage, i. e. meter reading is rendered independent 35 of supply voltage changes.

Figure 5 shows the performance of the circuit of Figure 4 with the resistance $R_c=50$ ohms, $R_m=200$ ohms, and various values of the feed-back circuit resistance R_s , the meter current I_m being plotted against the line voltage E_l . It will be noted that in the upper curve of this figure, R_s equals infinity, which represents the conditions of Figure 1 and corresponds to the curve 15 in Figure 3. It will be noted that with a resistance R_s of the value of 600 ohms exact compensation is produced so that the meter reading is independent of line voltage variations.

Figure 6 is the same as Figure 5, except that the measuring resistance R_m has been changed 55 from 200 to 150 ohms, thus shifting the level of the meter current and slightly altering the curve shapes. In this condition exact compensation for line voltage variations exists with $R_s=450$ ohms.

In general it may be shown that perfect compensation will be obtained when

$$R_s = \frac{R_m}{R_c} - K$$

where K is the constant of the ballast tube. The 65 equation of the voltage and the current of the ballast tube within its working range is $E=K-Q$ from which the constant K may be obtained, the performance within the working range as heretofore mentioned being approximately with value of 70 150 for K, and the constant Q being approximately 205. It should be noted that exact compensation exists only with a certain value of R_s for any value of R_m but through a considerable range of values of R_m , an average value or R_s provides very great improvement of voltage com-

pensation so that a very nearly perfect compensation and a very considerable improvement over the condition where R_s equals infinity, that is, where there is no compensating feed-back circuit, is obtained.

The circuit of Figure 4 in some ways resembles a plain bridge circuit, the parts being arranged as in a bridge circuit in Figure 7. Figure 7 is exactly like Figure 4, except for the different placing of the parts, but the performance is quite different from the usual bridge circuits since it does not operate on balance. The variation of R_m is read directly on the meter instead of being balanced out by variation of some other resistor. The current through the meter is almost equal to 15 the current of the measuring resistance R_m and much larger than in the resistance R_s , a condition quite impractical for the conventional Wheatstone bridge in usual operation. A further 20 difference from the usual bridge circuit is that the second variable resistance of the system, i. e., the ballast tube 10, varies primarily with line voltage and not meter-measured resistance, the variation being non-linear. Finally, and perhaps 25 the most important distinction, is that the meter operates as a straight current indicator of resistance exactly as in Figure 1. Thus, with R_s equal to 500 ohms and with 110 volts on the supply line, when R_m equals 150 ohms, the current through the meter is .349 amperes, while with R_m equaling 30 200 ohms the meter current is .273 amperes, which is exactly in inverse proportion to the variation of the measured resistance R_m . While in these diagrammatic figures, R_m has been represented as a resistance which it is desired to 35 measure, it should, of course, be understood that the variation in resistance in this element may itself be responsive to variations in some other characteristic of material to be measured, whereupon the meter reading becomes a measure of the 40 amount of this characteristic to be measured. It will be noted that this circuit is applicable to either direct or alternating current operation. It is of particular value in connection with alternating current since with such current the meter 45 does not differentiate between positive and negative current flow. In the ordinary bridge balance is indicated by zero current through the meter and unbalance in either direction in the case of alternating current flow would affect the 50 meter reading in the same manner. In the present case the desired condition of full voltage compensation is accompanied by a definite current flow through the meter and variations in the arm to be measured in one or the other direction is 55 accompanied by either an increase or a decrease of flow in accordance with the particular direction of the variation. This is of particular importance where responsive means are to be employed since it is then essential that direction as well as 60 amount of variation be taken into account.

Such a system is applicable not only to measure an electrical characteristic of a single element, but it is also applicable to the measurement of the differences between the characteristics of 65 two different elements. This is illustrated, for example, in Figure 8, which shows a circuit for measuring the differences of two inductances 70 and 31 arranged in a bridge circuit with the resistors 32 and 33. It is frequently desirable to 75 operate such an inductance bridge at a frequency higher than is directly available from convenient sources. To supply this higher frequency, there is shown an alternating current generator 34 (supplying power to the bridge circuit) through 75

the two leads 35 and 36. The generator 34 has a separate direct current exciter 37 for its field coil 38 driven directly from the shaft 39 of the generator 34. This exciter is provided with its own field coil 40. At M is shown the meter which is connected through the lines 41 and 42, a resistance 43 being interposed in line 42, to the full wave rectifier system comprising the rectifiers 44 from which connections are made through the lines 45 and 46 with the opposite corners of the bridge circuit between the inductances 38 and 31 and between the resistances 32 and 33 so that a measuring direct current is imposed on the meter terminals. This arrangement of motor 10 generator bridge circuit and meter does not, per 15 se, constitute this invention.

With a generator and exciter of the type shown any variation in the shaft speed causes a somewhat greater proportionate variation in the exciter voltage and a considerably larger variation 20 in the voltage of the generator 34, and with a bridge circuit operating "off balance" as in the diagram shown, variation in the supply circuit voltage across the bridge circuit produces a proportionate change in meter reading. Thus any 25 material variation in the shaft speed would cause a noticeable change in the meter reading if it were not compensated for. If we assume, for example, that with normal shaft speed there is 30 100% voltage on the exciter and 100% voltage on the alternator, if the shaft speed drops to 90%, the exciter voltage drops to 85% and the generator voltage to 75%, these variations being practically straight line. In accordance with the 35 present invention, however, these effects of generator voltage on the meter reading are compensated for by direct current derived from the exciter through the leads 50 and 51, in one of which is positioned the resistor 52, these connections to the meter being such as to oppose 40 variations in current derived from the measuring system due to voltage changes impressed on the bridge circuit. Assuming that the meter is a one milli-ampere full scale meter and that "normal" reading is at midscale, or one-half a milli-ampere, and if the resistances 43 and 52 are so 45 chosen that with normal voltage there is 1.25 milli-amperes "forward" current through the meter from the exciter compensator circuit through the lines 50 and 51 and a "reverse" current of .75 milli-ampere from the measuring circuit, then if the shaft speed falls to 90%, the exciter voltage would fall to 85% so that the compensating current fed from the exciter to the meter would 50 fall to 85% or 1.0625 milli-amperes forward while the meter current from the measuring circuit would fall to 75% or .5625 milli-ampere, giving a meter current of .5 milli-ampere; exactly the same as at 100% shaft speed. Any variation 55 in the inductances will be read as usual on the meter. With .25 milli-ampere on the meter from the measuring circuit the meter will read full scale while with the 1.25 milli-amperes it will read zero, the scale being straight line. Exact 60 compensation will exist, of course, only at midscale with the values chosen. The error at the top of the scale will be one-half of what it would be with no compensation, while at the bottom of the scale, which would have no error without the compensation, the error with compensation 65 will be the same as at the top of the scale.

This system is reverse in some respects to the straight voltage compensator circuit shown in Figure 4 in that the supply voltage produces a change of voltage across the measuring system

greater than the percentage change of the input and that the percentage change of the compensator voltage is less than the proportion of the voltage across the measuring circuit. However, the flexibility of the system is such that these conditions give full compensation at the center operating point of the meter scale. The essential elements are similar, however, to the system of Figure 4, there being a pair of impedances whose differences are to be measured instead of a single variable impedance, and it is a voltage variation rather than an impedance variation in the supply unit which is employed to produce the compensation.

Figure 8 illustrates an application of this method of voltage compensation to a capacity measuring system operating at high frequency. In this system high frequency power is supplied to the measuring circuit from a vacuum tube oscillator. This oscillator is shown as supplied with alternating current power through the transformer 60, one secondary coil 61 of which supplies energy to the plate 62 of the three-element vacuum tube 63 through a radio frequency choke impedance 64, while a secondary 65 of the transformer supplies current to the tube filament 66. The plate circuit also contains the capacity 67 and the inductance 68, which is coupled to the inductance 69 of the grid circuit, the grid being shown at 70. The grid circuit also contains the grid condenser 71 and the resistor 72. At 73 is shown a tuning condenser for the plate circuit. This circuit is coupled to a secondary circuit nearly in resonance therewith through a coupling condenser 74. This secondary circuit includes a measuring capacity 75 which may be made responsive to variations in some characteristics to be measured, this secondary including the coupled inductances 76 and 77, the capacity 78, and a high frequency voltmeter comprising the milliammeter 79, the rectifier 80 and the limiting resistance 81. This secondary circuit also includes the tuning reactance 85. This circuit so far described is not per se a part of this invention. Unless some provision were made for compensation, the meter reading would vary not only with variation of the characteristic measured, causing variation of the capacity 75, but also with any variation of voltage supplied to the transformer 60, and in accordance with this invention this variation in the supply voltage is compensated for as will now be described.

With an oscillator of the type shown in variation in the supply circuit voltage causes a variation in the output of the oscillator of a magnitude more than proportional to the variation of the supply voltage, and a variation of the grid current of the oscillator of even greater proportion than the output. Thus for a 10% increase in line voltage the output voltage to the oscillator may increase 15% and the grid current may increase 20%. Since the measuring circuit is coupled through a constant impedance to the oscillator, the voltage across any point in the measuring circuit, and specifically the voltage across the meter, varies in direct proportion to the voltage of the oscillator. Thus a 10% increase of supply voltage would produce a 15% increase in the oscillator voltage which would result in a 15% increase in the meter reading, other factors remaining constant. At the same time the grid current would increase by 20%. As shown, therefore, in this figure, a proportion of the grid current derived from a shunt including the resistance 82 tapped off from the grid resistor 72 at 83

and including the lead 84 to the meter is passed through the meter in a direction opposite to that of the measuring circuit current. This shunt is so chosen, in the values of the resistors 81 and 82 and the position of the tap 83, that at "normal" center scale operation of the meter the grid current flowing through the meter is one and one-half times the full scale current, while the measuring circuit current to the meter is twice full scale current, the difference between the two providing half scale current and causing the meter deflection to be at midscale. If now the supply voltage to the transformer 60 increases 10% there will be a 15% rise in the measuring 15 circuit current which increases from 2.0 to 2.3 times full scale current. At the same time there will be a 20% increase in the current derived from the grid current shunt, going from 1.5 times full scale to 1.8 times full scale current. The net 20 current in the meter will be thus 2.3 minus 1.8 times full scale current or 0.5 times full scale current, as it was before the voltage impressed on the transformer 60 changed. Thus at mid-scale the reading of the meter is unaffected. 25 When with a normal or 100% applied voltage the current from the measuring circuit decreases to 1.5 times full scale current due to change in the characteristic being measured affecting the capacity of the condenser 76 the current through 30 the meter is 1.5 times full scale current from the measuring circuit minus 1.5 times full scale current derived from the grid circuit, or zero current through the meter. In this case a 10% rise in applied voltage will cause the meter circuit 35 current to rise 15% as before or from 1.5 to 1.725 times full scale current, the grid current applied to the meter rising from 1.5 times to 1.8 times full scale current as before. Under these conditions there will be a change of .075 times full scale 40 deflection for a 10% shift of line voltage. Similarly when the characteristic of the material measured changes so that the meter current rises to 2.5 times full scale current, the net current through the meter will be exactly full scale current producing full scale deflection. Under such 45 conditions a rise of 10% in voltage will cause a rise in measuring circuit current of .375 times full scale deflection and will produce the same rise of .3 times full scale deflection in the grid current, 50 the difference producing a net rise or .075 times full scale deflection, which is the same as at zero meter scale but in the opposite direction.

The circuit shown is employed for "null" measurement, that is, the apparatus is so set that 55 when the characteristic measured is at its desired value the meter is at center scale, deviation from the desired value showing a deflection of the meter above or below the center scale position. It will be noted that the possible error due to line 60 voltage fluctuation varies as the distance of the meter from center scale. Thus, the possible error due to line voltage variation varies exactly as the error of the characteristic varies, a desirable arrangement since the greater the deviation, the 65 less the importance of the absolute accuracy of the measurement. It will be noted, however, that in the extreme case of variation of 10% in the line voltage a variation of only 7½% in scale reading is produced.

70 Figure 10 shows a circuit similar to Figure 9, except that instead of deriving the compensating meter current from the grid circuit, it is derived from a secondary winding 90 on the transformer 60 feeding through a choke 91 and a rectifier 92 to ground through the meter in opposition to the

current derived from the meter circuit. By employing the proper values of the various parts, it will be evident that exact compensation of the meter reading at any desired point for variations in line voltage supplied to the transformer 60 5 may be made similarly to the way in which this is done in the arrangement shown in Figure 9, except that in Figure 10 the voltage variations derived from the secondary 90 are equal to those of the supply and less than those of the measuring 10 circuit instead of being greater than those of the measuring circuit as in the arrangement of Figure 9.

Figure 11 illustrates an application of the invention to a system wherein the voltage compensation is applied to a circuit which may be employed for various purposes, this circuit being responsive to variations in a desired controlling characteristic value independent of variations in the energy supply source. This circuit is in general the same as that shown in Figure 8, except that a vacuum tube circuit is substituted for the meter circuit of Figure 8. This vacuum tube circuit may be used, for example, for initiating any desired of a great variety of controlling operations. In this Figure 11 the negative end of the resistor 52 is connected to the negative pole of the exciter and to the bridge circuit between the impedances 32 and 33. The cathode 100 of the vacuum tube 101 receives a negative direct current 30 potential from the exciter through the slide 102 and the grid 103 of the tube 101 as an alternating potential impressed thereon from between the impedances 30 and 31.

Under normal conditions, the negative potential from the exciter exceeds the peak value of the alternating potential from the measuring circuit by an amount sufficient so that the most positive potential of the grid of the tube when the alternating potential from the measuring 40 circuit is at peak is just sufficient to cause current flow in the plate circuit of the tube. Any decrease in the potential from the measuring circuit, thus reduces the peak potential on the grid to a point where current in the plate circuit does not flow, or in the case of a gas filled thermionic rectifier, the discharge is not started. Either with a conventional high vacuum tube or in the case of the gas filled rectifier this flow of current and its interruption by a decrease of potential from the measuring circuit can be applied to further controlling circuits as may be desired. 45

In the metering circuits shown, for example, in Figures 8, 9, and 10, it has been noted that the compensation is exact for only one meter reading, readings above and below this one reading being subject to variations caused by variations in line voltage. Exact compensation for all instrument readings may, however, be produced by the use of certain additional mechanism. One 55 example of this is shown in Figure 12, the circuit being substantially the same as that of Figure 9. The transformer secondaries 81 and 85 are not directly connected in Figure 12.

In this figure, the oscillator plate current flows 60 from the filament circuit at the point 120 through a resistor 116 back to the transformer winding 81 and to the tube plate 62 and through the tube to the filament 86. At the same time, the rectifier, in this case shown as a tube 112, flows a 65 current in proportion to the voltage of the intermediate circuit. This current flows from the filament 113 through the common point 120 to the potentiometer 115 and back through the intermediate coil 85 to the plate 111 and grid 121. 70

of the rectifier tube. A proportion of the voltage across the resistor 118 is picked up and opposes the potential through the resistor 116, the difference actuating the galvanometer element 117. 5 There is a mechanical connection from the galvanometer element 117 through a mechanism 118 to the slider 119 of the potentiometer 115. This actuating mechanism 118 is so arranged that the slider 119 moves governed by the current flow 10 through the galvanometer 117 in such a manner as to maintain a current through the galvanometer 117 constant. That is, if the current through the potentiometer 115 increases, potential of the slider 119 increases and tends to increase the flow of the current through the galvanometer 117 in the direction of the arrow below the galvanometer. This alters the deflection of the galvanometer 117 which acts through the actuating mechanism 118, moving slider 119 to 15 the left on potentiometer 115 thus reducing the proportion of the potential across the potentiometer which is picked up at 119. This action continues until the slider 119 has been moved to the left a sufficient amount to cause the predetermined flow of current to pass through the galvanometer 117. This mechanism 118 per se 20 being old and well known in the art, no detail description thereof is deemed necessary.

The reading of the circuit is taken by a reading of the position of the slider 119 on the potentiometer 115 as indicated by the scale shown. It will be noted that with any given line potential, the potential across the resistor 116 is a constant and the potential across the part of the 25 potentiometer 115 picked up by slider 119 is likewise a constant. If, as has been explained in the explanation of previous figures, the circuit constants are predetermined in a fashion such that the current through the galvanometer element 117 is constant, regardless of variation of line 30 voltage for a particular scale reading, that is, assuming that the potential across the resistor 116 and the potential across the potentiometer 115 picked off at the slider 119 vary by the same amount at a given current flow through the intermediate rectifier tube 110, then this condition of exact compensation will exist for all values of current through the rectifier 110, assuming, as may be done, that the proportionate 35 variation of current through the tube 110 with line voltage remains constant for varying currents through this rectifier tube. That this is the case is obvious, for an increase of current flow through the resistor 118 causes a reduction of the proportion pick up by slider 119, this motion being such that the net potential remains 40 constant.

In all of the illustrations of the invention hereinbefore given it will be noted that the potential and current variations in the system arising from variations of power supplied to the system are opposed by other potential and current variations arising from the same variations of power supply in such a manner that the variations to be measured are alone registered by the meter. To that end a portion of the current flow in the system, the proportion of which is variable with the supply voltage variation, is shunted about the meter so that the remaining measured current is independent of the supply voltage.

From the foregoing description of method and certain systems in which it is shown as employed, it should be evident to those skilled in the art that various changes and modifications might be made without departing from the spirit or

scope of this invention as defined by the appended claims.

I claim:

1. In combination, first, an electrical system including a controlling variable electrical means and a mechanism responsive to variations of said controlling means; second, a source of power supplying energy to said electrical system; third, power transmission means interposed between said source and said system, said means having a variable characteristic responsive proportionately to variations of said source; and fourth, means for feeding a predetermined amount of power from said source directly to said responsive mechanism, said amount of power being predetermined so that the variations thereof caused by variations of said source counteract the variations which would be caused in said responsive mechanism by variations in said source acting through said interposed means. 10 15 20

2. In combination, first, an electrical system including a controlling variable electrical means and a mechanism responsive to variations of said controlling means; second, a source of power supplying energy to said electrical system; third, power transmission means interposed between said source and said system, said means having a variable characteristic responsive proportionately to variations of said source; and fourth, means for feeding a current derived from said source directly to said responsive mechanism, said current varying due to variations in said source in amount equal and opposite to current variations reaching said responsive mechanism through said interposed means and caused by 30 35 the same variations in said source.

3. In combination, a measuring circuit including an impedance to be measured and a meter responsive to the amount of such impedance, a source of electric power, means interposed between said source and measuring circuit responsive in an electrical characteristic to variations in voltage of said source, and means responsive to changes in said characteristic for feeding power to said meter in directions to oppose changes in meter reading otherwise caused by 40 45 the same voltage changes of said source acting through said interposed means.

4. In combination, a measuring circuit including a variable impedance responsive in its variations to variations in a characteristic to be measured and a meter responsive to the amount of such impedance, a source of electric power, means interposed between said source and measuring circuit responsive in an electrical characteristic to variations in voltage of said source, and means also responsive in the same characteristic to voltage changes in said source for feeding power to said meter in directions to oppose changes in meter reading otherwise caused by 50 55 60 the same voltage changes of said source acting through said interposed means.

5. In combination, a measuring circuit including an impedance to be measured, a meter responsive to the amount of such impedance, a source of electric power connected to said measuring circuit, a voltage regulator between said source and measuring circuit, and a connection in parallel with said regulator from said source to said measuring circuit, and in opposed relation to said meter of the regulator-containing connection, for impressing on said meter energy opposed to that derived from said regulator-containing connection and variable with voltage changes of said source in amount to compensate 65 70 75

for energy changes due to the same voltage changes impressed on said regulator-containing connections.

6. In combination, a measuring circuit including an impedance to be measured, a meter responsive to the amount of such impedance, a source of electric power connected to said measuring circuit, a ballast tube between said source and measuring circuit, and a connection in parallel with said tube from said source to said measuring circuit, and in opposed relation to said meter of the tube-containing connection, for impressing on said meter energy opposed to that derived from said tube-containing connection and variable with voltage changes of said source in amount to compensate for energy changes due to the same voltage changes impressed on said tube-containing connections.

7. In combination with an alternating current generator, a direct current exciter coupled for rotation with said generator and exciting the field of said generator, a bridge circuit containing a pair of impedances the differences between which are to be measured, said bridge circuit being energized from said generator, a direct current meter, and measuring connections including a rectifier between said bridge circuit and meter, of a connection from the output of said exciter to said meter feeding energy to said meter in amount and direction to compensate for driving speed variations of said generator and exciter at a predetermined meter reading.

8. In combination with an impedance to be measured, a measuring circuit including said impedance, a meter in said measuring circuit, an oscillator circuit for supplying energy to said measuring circuit, and a source of alternating current power for energizing said oscillator circuit, said oscillatory circuit including an electron tube having a plate and a grid, said measuring circuit deriving energy from the plate circuit, of a connection from said grid circuit to said meter for supplying energy to said meter in amount and direction to oppose, by variations therein due to variations in voltage of said source, variations caused by said source-voltage variations in the energy supply to said meter derived through said measuring circuit.

9. In combination with an impedance to be measured, a measuring circuit including said impedance, a meter in said measuring circuit, an oscillatory circuit for supplying energy to said measuring circuit, and a source of alternating current power for energizing said oscillatory circuit, of a connection from said source to said meter for supplying energy to said meter in amount and direction to oppose, by variations therein due to variations in voltage of said source, variations caused by said source variations in the energy supply to said meter derived through said measuring circuit.

10. In combination with an impedance to be measured, a measuring circuit including said impedance, a meter in said measuring circuit, an oscillatory circuit for supplying energy to said measuring circuit, and means including a transformer for supplying alternating current energy to said measuring circuit, of a connection from said transformer to said meter for supplying energy thereto in amount and direction to substantially balance out in the reading of said meter variations due to voltage variations in said transformer transmitted thereto through said measuring circuit.

11. In combination with an impedance to be measured, a measuring circuit including said impedance, a direct current meter in said measuring circuit, an oscillatory circuit for supplying energy to said measuring circuit, and means including a transformer for supplying alternating current energy to said measuring circuit, of a connection from said transformer to said meter for supplying energy thereto in amount and direction to substantially balance out, in the reading of said meter, variations due to voltage variations in said transformer transmitted thereto through said measuring circuit.

12. An electrical system suitable for alternating current and comprising a bridge having an impedance in one arm variable with the current passing therethrough, and having impedances in the other three arms of said bridge, said bridge including a cross connection between the junctions of the two arms of each pair, said impedances being so proportioned that with a definite current flow in said cross connection said current flow is substantially unaffected by voltage changes impressed on the terminals of said bridge.

13. In a system for measuring a variable impedance by measuring current flow, the method of compensating for current variations arising from variations in voltage applied to said system, which comprises shunting about a current measuring device in said system a portion of the current flow in the system, the proportion shunted being so variable with supply voltage that the remaining and measured current is independent of supply voltage.

14. In a system of measuring a variable impedance, the method of compensating for potential variation arising from variation of power supplied to the system, which comprises opposing said potential variation against further potential variation arising from said variation of power supply and having a predetermined relation thereto such that the resultant difference while variable with variation in said variable impedance is independent of said power supply variation.
